(57) **ABSTRACT**

A waste toner collecting device includes an intermediate collection box, a conveying path, a conveying screw, an exhaust path and a floating toner collection chamber. The conveying path is provided in the intermediate collection box. The conveying screw is rotatable in the conveying path. Through the exhaust path, air containing a floating toner is sucked and passed. The floating toner collection chamber is provided on a part of the exhaust path in the intermediate collection box. The floating toner collection chamber has a discharge opening opened to an inside of the intermediate collection box and a discharge door. Rotation of the conveying screw in a normal direction turns the discharge door into a storage position where the discharge opening is closed. Rotation of the conveying screw in a reverse direction turns the discharge door into a discharge position where the discharge opening is opened.

INCORPORATION BY REFERENCE

This application is based on and claims the benefit of priority from Japanese Patent application No. 2016-061371 filed on Mar. 25, 2016, which is incorporated by reference in its entirety.

BACKGROUND

The present disclosure relates to a waste toner collecting device which collects a waste toner including a toner removed by a cleaning device and a scattered toner, and an image forming apparatus including the waste toner collecting device.

In an electrophotographic type image forming apparatus, such as a copying machine, a printer and a facsimile, a powder developer is mainly used. A latent image formed on an image carrier such as a photosensitive drum is visualized into a toner image with the developer (a toner) supplied from a developing device. The toner image is transferred on a sheet directly or via an image carrier such as an intermediate transferring belt, and then fixed on the sheet. The toner remained on the image carrier after the transferring is removed by a cleaning device, conveyed to a waste toner collection container by a conveying member such as a conveying screw to be collected.

On the other hand, when the latent image is visualized into the toner image by the developing device, some of the toner may be scattered, leaked out from the developing device and contaminate an inside of the image forming apparatus. Thereby, the image forming apparatus is sometimes provided with a floating toner collection container. In such a floating toner collection container, air including the scattered toner in the developing device (hereinafter, called as a floating toner) is sucked by a suction device, the floating toner is separated from the air and then collected.

However, in many cases, the floating toner collection container is provided separately from the waste toner collection container in which the waste toner removed from the image carrier by the cleaning device is collected. Thereby, if each container is filled with the collected toner, it is necessary to replace the floating toner collection container and the waste toner collection container separately, and a replacement work may be performed frequently. In addition, it is necessary to secure space where the floating toner collection container and the waste toner collection container are disposed, and thus the image forming apparatus may become large in size.

To solve the above problems, a suction path through which the floating toner is sucked may be provided in the waste toner collection container. In this case, although a space saving of the image forming apparatus becomes possible, because the toner collected in the waste toner collection container is also sucked through the suction path, suction force of the floating toner is lowered, and the floating toner cannot be efficiently removed.

SUMMARY

In accordance with an aspect of the present disclosure, a waste toner collecting device includes an intermediate collection box, a waste toner collection container, a conveying path, a conveying screw, an exhaust path and a floating toner

collection chamber. The intermediate collection box stores a toner removed from an image carrier by a cleaning device. In the waste toner collection container, the toner stored in the intermediate collection box is collected. The conveying path is formed on a bottom face of the intermediate collection box. The conveying screw is supported in the conveying path so as to be rotatable in a normal direction and in a reverse direction. The conveying screw conveys the stored toner toward the waste toner collection container by rotating in the normal direction. Through the exhaust path, air containing a floating toner is sucked and passed. The floating toner collection chamber is provided on a part of the exhaust path and stores the floating toner separated from the air. The floating toner collection chamber is provided in the intermediate collection box. The floating toner collection chamber has a discharge opening and a discharge door. The discharge opening is opened to an inside of the intermediate collection box. The discharge door is interfered with the conveying screw as the conveying screw is rotated. The discharge door is turned between a storage position where the discharge opening is closed and a discharge position where the discharge opening is opened. Rotation of the conveying screw in the normal direction turns the discharge door into the storage position. Rotation of the conveying screw in the reverse direction turns the discharge door into the discharge position so that the floating toner stored in the floating toner collection chamber is discharged in the conveying path through the discharge opening.

In accordance with an aspect of the present disclosure, an image forming apparatus includes a developing device, a cleaning device and the above described waste toner collecting device. The developing device forms a toner image on an image carrier. The cleaning device removes the toner on the image carrier.

The above and other objects, features, and advantages of the present disclosure will become more apparent from the following description when taken in conjunction with the accompanying drawings in which a preferred embodiment of the present disclosure is shown by way of illustrative example.

BRIEF DESCRIPTION OF THE DRAWINGS

FIG. 1 is a front view showing a structure of an image forming apparatus according to an embodiment of the present disclosure.

FIG. 2 is a front view showing an image forming part of the image forming apparatus according to the embodiment of the present disclosure.

FIG. 3 is a front sectional view showing a structure of a developing device of the image forming apparatus according to the embodiment of the present disclosure.

FIG. 4 is a front side perspective view showing a waste toner collecting device according to an embodiment of the present disclosure.

FIG. 5 is a front side perspective view showing a floating toner collection chamber in the waste toner collecting device according to the embodiment of the present disclosure.

FIG. 6 is a front side perspective view showing an inside of the floating toner collection chamber in the waste toner collecting device according to the embodiment of the present disclosure.

FIG. 7 is a rear side perspective view showing the waste toner collecting chamber according to the embodiment of the present disclosure.

FIG. 8 is a sectional perspective view showing the floating toner collection chamber of which a discharge opening is

closed with a discharge door, in the waste toner collecting device according to the embodiment of the present disclosure.

FIG. 9 is a sectional perspective view showing the floating toner collection chamber of which the discharge opening is opened with the discharge door, in the waste toner collecting device according to the embodiment of the present disclosure.

FIG. 10 is a front view showing a protruding piece and a spiral blade, in the waste toner collecting device according to the embodiment of the present disclosure.

FIG. 11A is a side view showing the discharge door turned into a storage position, in the waste toner collecting device according to the embodiment of the present disclosure.

FIG. 11B is a side view showing the discharge door turned into a discharge position, in the waste toner collecting device according to the embodiment of the present disclosure.

FIG. 12A is a front view showing the spiral blade coming into contact with an inclined edge of the protruding piece, in the waste toner collecting device according to the embodiment of the present disclosure.

FIG. 12B is a front view showing the spiral blade coming into contact with a tip edge of the protruding piece, in the waste toner collecting device according to the embodiment of the present disclosure.

DETAILED DESCRIPTION

Hereinafter, with reference to figures, a waste toner collecting device 40 and an image forming apparatus 100 according to an embodiment of the present disclosure will be described.

With reference to FIGS. 1 and 2, the image forming apparatus 100 according to an embodiment of the present disclosure will be described. FIG. 1 is a front view showing a structure of the image forming apparatus 100 and FIG. 2 is a sectional view showing an image forming part Pa. The image forming apparatus 100 of the embodiment is a quadruple tandem type color printer including four image forming parts Pa, Pb, Pc and Pd which are adjacently arranged and form a full color image. The four image forming parts Pa, Pb, Pc and Pd respectively correspond to four different colors (magenta, cyan, yellow and black). In the following description, a front side of a paper plan of FIG. 1 shows a front side of the image forming apparatus 100, and left and right directions are based on a direction in which the image forming apparatus 100 is seen from the front side. Fr, Rr, L and R in each figure respectively show a front side, a rear side, a left side and a right side.

In an apparatus main body of the image forming apparatus 100, the four image forming parts Pa to Pd are adjacently arranged in the order from the right side of FIG. 1. These image forming parts Pa to Pd sequentially form images of magenta, cyan, yellow and black by a charging process, an exposing process, a developing process and a transferring process.

In these image forming parts Pa to Pd, photosensitive drums 1a, 1b, 1c and 1d are respectively provided so as to be rotatable in the counterclockwise direction in FIG. 1. The photosensitive drums 1a to 1d are image carriers each of which carries a visible image (a toner image) of each color. Above the photosensitive drums 1a to 1d, an intermediate transferring belt 8 is bridged between a driven roller 10 and a driving roller 11. The intermediate transferring belt 8 is an image carrier which carries a visible image (a toner image) formed by overlapping the visible image of each color. The intermediate transferring belt 8 rotates in the clockwise

direction at the same liner velocity as that of the photosensitive drums 1a to 1d. In an inner hollow space of the intermediate transferring belt 8, first transferring rollers 6a, 6b, 6c and 6d are rotatably supported. The first transferring rollers 6a to 6d respectively oppose to the photosensitive drums 1a to 1d via the intermediate transferring belt 8. On the left side of the driving roller 11, a secondary transferring roller 9 is rotatably supported. The secondary transferring roller 9 opposes to the driving roller 11 via the intermediate transferring belt 8.

On a downstream side of the secondary transferring roller 9 in a rotation direction of the intermediate transferring belt 8 (near the driven roller 10), a belt cleaning device 19 is disposed. The belt cleaning device 19 removes the toner and the others remained on a surface of the intermediate transferring belt 8. The belt cleaning device 19 has a blade and a collection part. The blade comes into contact with the intermediate transferring belt 8 from a counter direction to the rotation direction of the intermediate transferring belt 8. The toner removed by the blade is collected in the collection part. The toner collected in the collection part is conveyed toward the front side of the image forming apparatus 100 by a collection spiral. On a front face of the collection part, a discharge opening through which the conveyed toner is discharged is formed.

A sheet P on which the toner image is to be transferred is stored in a sheet feeding cassette 16 provided in a lower portion of the apparatus main body. The sheet P is conveyed to the secondary transferring roller 9 via a feed roller 12a and a registration roller pair 12b.

Next, the image forming parts Pa to Pd will be described. In the image forming parts Pa to Pd, charging devices 2a, 2b, 2c and 2d, developing devices 3a, 3b, 3c and 3d and drum cleaning devices 7a, 7b, 7c and 7d are respectively disposed around the photosensitive drums 1a to 1d. The charging devices 2a to 2d charge the photosensitive drums 1a to 1d respectively. The developing devices 3a to 3d develop latent images formed on the photosensitive drums 1a to 1d with the toner respectively. The drum cleaning devices 7a to 7d remove and collect the developer (the toner) remained on the photosensitive drums 1a to 1d respectively after the toner images are transferred. Below the image forming parts Pa to Pd, an exposing unit 5 is disposed. The exposing unit 5 performs exposing to the photosensitive drums 1a to 1d according to an image data.

Next, an image forming operation will be described. When the image data is input from a host apparatus such as a personal computer, the charging devices 2a to 2d respectively charge the surfaces of the photosensitive drums 1a to 1d uniformly, and then the exposing unit 5 performs the exposing to the photosensitive drums 1a to 1d according to the input image data to form latent images corresponding to the input image data on the photosensitive drums 1a to 1d.

The latent images are developed by the developing devices 3a to 3d into toner images of corresponding colors. Then, by applying a predetermined transferring voltage between the first transferring rollers 6a to 6d and the photosensitive drums 1a to 1d, the toner images of magenta, cyan, yellow and black colors are first-transferred on the intermediate transferring belt 8. After that, in order to prepare for formation of next new latent images on the photosensitive drums 1a to 1d, the toner remained on the surfaces of the photosensitive drums 1a to 1d are removed by the drum cleaning devices 7a to 7d respectively. If a ratio of the toner to the two component developer filled in each of the developing devices 3a to 3d is lower than a predetermined value by the

image forming operation described later, the toner is supplied to the developing devices **3a** to **3d** from toner containers **4a** to **4d** respectively.

The toner images formed on the photosensitive drums **1a** to **1d** are sequentially transferred on the intermediate transferring belt **8** which rotates in coming into contact with the photosensitive drums **1a** to **1d**. Then, a full color toner image is secondary-transferred on the sheet **P** by the secondary transferring roller **9**. The full color toner image is heated and pressed at a fixing device **13** to be fixed on the sheet **P**. The sheet **P** on which the full color toner image has been fixed is ejected by an ejection roller pair **15** on the ejection tray **7**.

With reference to FIG. 2, the image forming part **Pa** described above will be described in detail. The image forming parts **Pb** to **Pd** each have the substantially same structure as the image forming part **Pa**, and their detail descriptions are omitted. Around the photosensitive drum **1a**, the charging device **2a**, the developing device **3a**, the first transferring roller **6a** and the cleaning device **7a** described above are arranged along a rotation direction of the photosensitive drum **1a** (the counterclockwise direction in FIG. 2).

The charging device **2a** has a charging roller **20** and a cleaning roller **21**. The charging roller **20** comes in contact with the surface of the photosensitive drum **1a** and applies a charging voltage on photosensitive drum **1a**. The cleaning roller **21** cleans the charging roller **20**.

The drum cleaning device **7a** has a rubbing roller **22**, a cleaning blade **23** and a collection spiral **24**. The rubbing roller **22** comes in pressure contact with the photosensitive drum **1a** at a predetermined pressure.

The cleaning blade **23** is supported on a downstream side of the contact portion of the rubbing roller **22** and the photosensitive drum **1a** in the rotation direction of the photosensitive drum **1a**, and comes in contact with the photosensitive drum **1a** from a counter direction to the rotation direction of the photosensitive drum **1a**.

The collection spiral **24** conveys the toner removed from the surface of the photosensitive drum **1a** by the rubbing roller **22** and the cleaning blade **23** to the front side of the image forming apparatus **100**. On a front face of the drum cleaning device **7a**, a discharge opening through which the conveyed toner is discharged is formed.

Next, with reference to FIG. 3, the developing device **3a** will be described. FIG. 3 is a sectional view showing a vicinity around the developing device **3a**.

The developing device **3a** has a development container **30** in which the two component developer containing a magnetic carrier and a toner (hereinafter, called as the developer) is contained. The development container **30** is divided by a partition wall **30a** into an agitating/conveying chamber **31** and a supplying/conveying chamber **32**. In the agitating/conveying chamber **31** and the supplying/conveying chamber **32**, an agitating/conveying screw **33a** and a supplying/conveying screw **33b** are rotatably disposed respectively. The agitating/conveying screw **33a** and the supplying/conveying screw **33b** mix the toner supplied from the toner container **4a** (refer to FIG. 1) with the magnetic carrier, agitate them and charge the toner.

In the agitating/conveying chamber **31** and the supplying/conveying chamber **32**, the developer is agitated and conveyed by the agitating/conveying screw **33a** and the supplying/conveying screw **33b** in an axis direction of each screw (a perpendicular direction to the paper plan of FIG. 3). The developer circulates between the agitating/conveying chamber **31** and the supplying/conveying chamber **32**.

through developer passing paths (not shown) formed at both end portion of the partition wall **30a**.

The development container **30** extends in the left upper oblique direction in FIG. 3. The development container **30** has an opening **30b** formed at a portion opposing to the photosensitive drum **1a**. In the development container **30**, a magnetic roller **34** and a developing roller **35** are disposed. The magnetic roller **34** is positioned opposite to the supplying/conveying screw **33b** in the vertical direction. The developing roller **35** is positioned opposite to the magnetic roller **34** in the left upper oblique direction. A part of an outer circumferential face of the developing roller **35** is exposed through the opening **30b** and opposes to the photosensitive drum **1a**. The magnetic roller **34** and the developing roller **35** are rotated in the clockwise direction in FIG. 3.

On an upstream side of the opposing area **R** of the developing roller **35** and the magnetic roller **34** in a rotation direction of the magnetic roller **34**, a regulating blade **36** is attached along a length direction of the magnetic roller **34** (a perpendicular direction to the paper plan of FIG. 3). Between a tip edge of the regulating blade **36** and an outer circumferential face of the magnetic roller **34**, a small gap is formed.

As described above, the developer is agitated while circulating between the agitating/conveying chamber **31** and the supplying/conveying chamber **32** in the development container by the agitating/conveying screw **33a** and the supplying/conveying screw **33b**. This charges the toner. The developer containing the charged toner is conveyed to the magnetic roller **34** by the supplying/conveying screw **33b** to form a magnetic brush around the magnetic roller **34**. A thickness of the magnetic brush is regulated by the regulating blade **36**. The magnetic brush of which the thickness has been regulated is conveyed to the opposing area **R** of the magnetic roller **34** and the developing roller **35**. At the opposing area **R**, the magnetic brush forms a toner layer on the developing roller **35** by voltage difference between a DC voltage applied to the magnetic roller **34** and a DC voltage applied to the developing roller **35** and magnetic field generated by the magnetic roller **34**.

The toner layer formed on the developing roller **35** is conveyed by the rotation of the developing roller **35** to an opposing area (a developing area) where the photosensitive drum **1a** and the developing roller **35** are opposite to each other. Because the predetermined voltage is applied to the developing roller **35**, the toner flies from the developing roller **35** to the photosensitive drum **1a** owing to voltage difference between the developing roller **35** and the photosensitive drum **1a**, and develops the latent image on the photosensitive drum **1a**.

The development container **30** has a suction opening **37** on a downstream side of the opposing area of the photosensitive drum **1a** and the developing roller **35** in the rotation direction of the developing roller **35**. Into the suction opening **37**, air containing a floating toner existing near the developing roller **35** is sucked. To the suction opening **37**, a floating toner duct **38** is connected. The floating toner duct **38** extends to the front side of the image forming apparatus **100**.

On a front end of the agitating/conveying chamber **31**, a developer discharge opening (not shown) is formed. Through the developer discharge opening, an excessive developer produced in the agitating/conveying chamber **31** and the supplying/conveying chamber **32** as the result of supplying the developer is discharged.

The image forming apparatus **100** further includes a waste toner collecting device **40** which collects the toner removed

by the drum cleaning devices 7a to 7b, the toner removed by the belt cleaning device 19, the floating toner existing near the developing rollers 35 of the developing devices 3a to 3d and the excessive developer in the developing devices 3a to 3d.

With reference to FIGS. 4 to 7, the waste toner collecting device 40 will be described. FIG. 4 is a front side perspective view showing the waste toner collecting device 40. FIG. 5 is a front side perspective view showing a floating toner collection chamber 55. FIG. 6 is a front side perspective view showing an inside of the floating toner collection chamber 55. FIG. 7 is a rear side perspective view showing the waste toner collecting device 40.

The waste toner collecting device 40 includes an intermediate collection box 50, a waste toner collection container 70 and floating toner collection chambers 55. The intermediate collection box 50 is disposed on the front side of the image forming parts Pa to Pd. In the intermediate collection box 50, the removed toner is temporarily stored. The waste toner collection container 70 is disposed below the intermediate collection box 50. In the waste toner collection container 70, the removed toner is finally collected. The floating toner collection chambers 55 are provided inside of the intermediate collection box so as to correspond to the image forming parts Pa to Pd. In the floating toner collection chambers 55, the floating toner is temporarily stored.

As shown in FIG. 4, the intermediate collection box 50 has a width and a height respectively corresponding to a width and a height of the four image forming parts Pa to Pd, and a predetermined thickness. The intermediate collection box 50 has a base part 50a and a lid part 50b which forms a horizontally long parallelepiped hollow space S1. The base part 50a is formed with removed toner receiving openings 51 and floating toner receiving openings 53 (refer to FIG. 6 also). The removed toner receiving openings 51 are connected to the discharge openings of the drum cleaning devices 7a to 7d. The floating toner receiving openings 53 are connected to the floating toner ducts 38 of the developing devices 3a to 3d. The base part 50a is further formed with waste developer receiving openings 52 and a removed toner receiving opening 54. The waste developer receiving openings 52 are connected to the developer discharge openings of the developing devices 3a to 3d. The removed toner receiving opening 54 is connected to the discharge opening of the belt cleaning device 19.

On a bottom face of the intermediate collection box 50, a conveying path 50c is formed along the left and right directions. The toner and the developer received through the removed toner receiving openings 51 and 54 and the waste developer receiving openings 52 are fallen on the conveying path 50c by their own weight.

On the conveying path 50c, a conveying screw 60 is rotatably supported. The conveying screw 60 is a conveying member which conveys the stored toner. The conveying screw 60 has a rotating shaft 60a and a spiral blade 60b. The spiral blade 60b is spirally formed around the rotating shaft 60a in an axis direction of the rotating shaft 60a at constant pitches. To one end portion of the rotating shaft 60a, a gear 61 is fixedly attached. The gear 61 transmits rotation force from a driving source (not shown) to the rotating shaft 60a. As the driving source, a motor which rotates the feed roller 12a may be used, for example. The motor has a clutch which allows the rotating shaft 60a to be rotated in a normal direction and a reverse direction.

At a right end portion of a bottom face of the conveying path 50c, a connection pipe 62 connected to the waste toner collection container 70 is connected. On rotating in the

normal direction, the conveying screw 60 conveys the toner and developer fallen on the conveying path 50c rightward in FIG. 4. The toner and developer is conveyed along the conveying path 50c and then collected into the waste toner collection container 70 through the connection pipe 62. The waste toner collection container 70 can be detachably attached to the connection pipe 62. The waste toner collection container 70 has a sensor which detects an amount of the collected toner and developer. When the sensor detects that a predetermined amount of toner and developer is collected, the waste toner collection container 70 is detached from the connection pipe 62 and the collected toner and developer is discarded.

As shown in FIGS. 5 and 6, the floating toner collection chamber 55 has a partition wall 55a and a lid part 65. The partition wall 55a is stood on the base part 50a so as to surround an area containing the floating toner receiving opening 53. The lid part 65 covers a space surrounded by the partition wall 55a. The partition wall 55a, the lid part 65 and the base part 50a form a horizontally long parallelepiped hollow space S2. The hollow space S2 is isolated from the hollow space S1 of the intermediate collection box 50. The floating toner receiving opening 53 is positioned at a right end portion of the floating toner collection chamber 55.

As shown in FIG. 6, at a left end portion of the floating toner collection chamber 55, an exhaust opening 56 is formed on the base part 50a. Through the exhaust opening 56, the hollow space S2 is evacuated. On the exhaust opening 56, an air filter 57 is attached with an obliquely downward posture. The air filter 57 blocks passing of the toner but allows passing of air.

As shown in FIG. 7, on a rear face of the base part 50a, an exhaust duct 63 is connected to each exhaust opening 56. The exhaust ducts 63 are joined to a center of the base part 50a in the left and right directions. On a joint portion 63a to which the exhaust ducts 63 are joined, an exhaust fan 64 is disposed. In this way, the floating toner duct 38 of each of the developing devices 3a to 3d, the floating toner collection chamber 55 and the exhaust duct 63 form an exhaust path 59 through which the air containing the floating toner existing near the developing roller 35 of each of the developing devices 3a to 3d is passed. That is, the floating toner collection chamber 55 forms a middle portion extending from the floating toner receiving opening 53 to the exhaust opening 56 between the floating toner duct 38 and the exhaust duct 63 in the exhaust path 59.

When the exhaust fan 64 is driven, pressure inside of each exhaust duct 63 becomes negative, and pressure inside of each floating toner collection chamber 55 and each floating toner dust 38 become also negative. As a result, the air containing the floating toner existing near each developing roller 35 of the developing devices 3a to 3d is sucked through the floating toner duct 38 into the floating toner collection chamber 55. In the floating toner collection chamber 55, the floating toner contained in the sucked air is collected by the air filter 57 and then stored in the floating toner collection chamber 55. On the other hand, the air is passed through the exhaust duct 63 and then discharged outside by the exhaust fan 64.

As shown in FIGS. 5 and 6, the partition wall 55a of the floating toner collection chamber 55 is formed with a protruded portion 55b such that the hollow space S2 of the floating toner collection chamber 55 extends downward from below the air filter 57. At a lower corner of the protruded portion 55b, a discharge opening 55c opened in an

oblique lower direction is formed. The discharge opening 55c is opened and closed by a discharge door 65a, as shown in FIG. 5.

With reference to FIGS. 8 to 10, the discharge door 65a will be described. FIG. 8 is a sectional perspective view showing the discharge opening 55c closed by the discharge door 65a. FIG. 9 is a sectional perspective view showing the discharge opening 55c opened by the discharge door 65a. FIG. 10 is a front view showing a protruding piece 67 and the spiral blade 60b.

The discharge door 65a is connected to the lid part 65, and turned between a storage position (refer to FIG. 8) and a discharge position (refer to FIG. 9) around an axis approximately parallel to the rotating shaft 60a of the conveying screw 60. In the storage position, the discharge door 65a closes the discharge opening 55c. In the discharge position, the discharge door 65a is turned toward the hollow space S1 of the intermediate collection box 50 and opens the discharge opening 55c. As shown in FIG. 8, in the storage position, the discharge door 65a extends in an oblique lower direction from the lid part 65. As shown in FIG. 9, in the discharge position, the discharge door 65a extends from the lid part 65 downward toward the conveying screw 60 supported by the conveying path 50c. The discharge door 65a is biased by a biasing member 66 to the storage position. The biasing member 66 is made of elastic material, such as urethane foam, for example. The biasing member 66 is interposed between the lid part 50b of the intermediate collection box 50 and the discharge door 65a.

At a tip edge of the discharge door 65a, a protruding piece 67 is fixedly attached. As shown in FIG. 10, the protruding piece 67 is formed into a trapezoidal shape in a front view, and has a tip edge 67a and inclined side edges 67b inclined in a direction in which they are approaching each other toward the tip edge 67a. The protruding piece 67 is made of elastic material, such as PET film. The protruding pieces 67 has a width W2 narrower than a pitch W1 of the spiral blade 60b of the conveying screw 60, and extends in a space between the adjacent spiral blades 60b of the conveying screw 60.

With reference to FIGS. 11A, 11B, 12A and 12B, a tuning operation of the discharge door 65a will be described. FIG. 11A is a side view showing the discharge door 65a turned to the storage position. FIG. 11B is a side view showing the discharge door 65a turned to the discharge position. FIG. 12A is a front view showing the spiral blade 60b coming into contact with the inclined edge 67b of the protruding piece 67. FIG. 12B is a front view showing the spiral blade 60b coming into contact with the tip edge 67a of the protruding piece 67.

As shown by a two-dotted line in FIG. 11A, in a state where the protruding piece 67 extends in the space between the adjacent spiral blades 60b, when the conveying screw 60 rotates in the normal direction (the counterclockwise direction in FIG. 11A) in order to convey the toner and developer fallen on the conveying path 50c, the spiral blade 60b comes in contact with the protruding piece 67. Then, as shown by a solid line in FIG. 11A, an outer circumferential face of the spiral blade 60b presses the protruding piece 67 in a rotation direction of the spiral blade 60b as the rotating shaft 60a rotates. By being pressed by the spiral blade 60b, the protruding piece 67 is deformed and bent with respect to the discharge door 65a.

When the spiral blade 60b comes into contact with the protruding piece 67, as shown in FIG. 12A, a corner between the outer circumferential face and a front side face of the spiral blade 60b in a conveying direction (X in FIGS. 12A

and 12B) comes into contact with the inclined side edge 67b on a rear side in the conveying direction. Then, as shown in FIG. 12B, the outer circumferential face of the spiral blade 60b comes into contact with the tip edge 67a of the protruding piece 67 and presses the protruding piece 67 in the normal direction. Because the discharge door 65a is biased by the biasing member 66 to the storage position, the discharge door 65a is not largely turned by the conveying screw 60.

On the other hand, when the conveying screw 60 is rotated in the reverse direction, as shown in FIG. 11B, the protruding piece 67 is pressed in the reverse direction by the outer circumferential face of the spiral blade 60b, and the discharge door 65a is turned to the discharge position against biasing force of the biasing member 66. The turning operation of the discharge door 65a is a reverse operation to the turning operation in the case where the conveying screw 60 is rotated in the normal direction, and its detail description is omitted. When the discharge door 65a is turned to the discharge position, the floating toner stored in the floating toner collection chamber 55 is fallen on the conveying path 50c through the discharge opening 55c. When the rotation of the conveying screw 60 in the reverse direction is stopped, the discharge door 65a is biased by the biasing member 66 to the storage position so that the discharge opening 55c is closed.

A toner collecting operation of the waste toner collecting device 40 having the above described configuration will be described. During the image forming operation, as described above, the toner remained on the photosensitive drums 7a to 7d in the image forming parts Pa to Pd is removed by the drum cleaning devices 7a to 7d, respectively. The removed toner is temporarily stored in the intermediate collection box 50 through the removed toner receiving openings 51. In addition, the toner remained on the intermediate transferring belt 8 after the secondary transferring is removed by the belt cleaning device 19 and then temporarily stored in the intermediate collection box 50 through the removed toner receiving opening 54. Furthermore, the waste developer is temporarily stored in the intermediate collection box 50 through the waste developer receiving openings 52. The toner and waste developer received from the receiving openings is fallen on the conveying path 50c by their own weight.

In the conveying path 50c, the conveying screw 60 is driven by the driving source to be rotated in the normal direction and conveys the fallen toner and developer in the conveying direction (rightward). After being conveyed to a right end of the conveying path 50c, the toner and developer is then collected into the waste toner collection container 70 through the connection pipe 62.

On the other hand, when the exhaust fan 64 is driven at a suitable timing, the air containing the floating toner near the developing rollers 35 of the developing devices 3a to 3d is sucked into the exhaust path 59 including the floating toner ducts 38, the floating toner collection chambers 55 and the exhaust ducts 63. In the floating toner collection chamber 55 which is a part of the exhaust path 59, the toner is collected by the air filter 57. The collected toner is fallen by its own weight and accumulates on upper faces of the partition wall 55a and the discharge door 65a. On the other hand, the air passing through the air filter 57 is discharged outside through the exhaust duct 63 by the exhaust fan 64.

When an amount of the accumulated toner becomes a predetermined amount, the conveying screw 60 is made to be rotated in the reverse direction for a predetermined period. For instance, the conveying screw 60 is made to be

rotated in the reverse direction for 2 to 3 seconds for every 1000 sheets. Then, the spiral blade 60b of the conveying screw 60 turns the discharge door 65a to the discharge position against the biasing force of the biasing member 66, as described above. Thereby, the discharge opening 55c is opened so that the floating toner accumulated on the upper faces of the discharge door 65a and the others is fallen on the conveying path 50c. The fallen toner is conveyed along the conveying path 50c by the conveying screw 60 together with the collected toner and developer, and collected into the waste toner collection container 70.

In the present embodiment, as described above, the floating toner collection chamber 55 in which the floating toner is temporarily stored is provided in the intermediate collection box 50 in which the toner removed by the drum cleaning devices 7a to 7d and the belt cleaning device 19 is temporarily stored. And, the floating toner stored in the floating toner collection chamber 55 can be discharged into the intermediate collection box 50. That is, it is not necessary to provide a floating toner collection container separately from the waste toner collection container 70. Accordingly, a number of replacement work of the collection containers can be reduced compared with a case where the floating toner collection container and the waste toner collection container 70 are separately provided so that the maintenance performance can be improved.

In addition, because it is not necessary to provide a floating toner collection container, enlargement in size of the image forming apparatus 100 can be inhibited. Furthermore, when a detecting sensor which detects the toner collection container being full is provided, only one of the detecting sensor is required so that a configuration of the waste toner collecting device can become simple and cost of it can be reduced.

In addition, the discharge door 65a is interfered with the spiral blade 60c as the conveying screw 60 is rotated, and turned to open and close the discharge opening 55c so that a dedicated tuning mechanism of the discharge door 65a for opening and closing the discharge opening 55c is not required. Accordingly, a configuration of the waste toner collecting device 40 can become simple.

In the embodiment, the protruding piece 67 of the discharge door 65a is pressed in the direction of the rotation direction of the spiral blade 60b. However, the protruding piece 67 may be pressed by the spiral blade 60b in the conveying direction and in an opposing direction to the conveying direction. In this case, the discharge door 65a may be supported so as to be rotatable around an axis perpendicular to the rotating shaft 60a of the conveying screw 60. And, the protruding piece 67 is made to be extended into a space between the spiral blades 60b. Thereby, when the rotating shaft 60a is rotated, a front side face or a rear side face of the spiral blade 60b in the conveying direction presses the protruding piece 67 in a front side direction or a rear side direction in the conveying direction to turn the discharge door 65a and to open or close the discharge opening 55c.

In addition, because the discharge door 65a of the floating toner collection chamber 55 is biased to the storage position by the biasing member 66, the discharge opening 55c is closed in a state where the conveying screw 60 is not rotated. Accordingly, when the exhaust fan 64 is driven to make the inside of the exhaust path 59 negative pressure, decrease in the suction force of the exhaust path 59 can be prevented.

In addition, use of the air filter 57 can separate the floating toner from the sucked air. Furthermore, because the discharge opening 55c is positioned below the air filter 57, the

toner collected by the air filter 57 can be fallen through the discharge opening 55c effectively.

The embodiment disclosed in this disclosure is considered to be illustrative in all points but to be restricted. The scope of the disclosure is shown by the scope of the claims not by the detailed description described above, and contains modification of or within an equivalent meanings of the scope of the claims. For instance, although the above embodiment was described in a case where configurations of the disclosure are applied to the color printer, the disclosure is not limited to the embodiment. The configurations of the disclosure may be applied to various image forming apparatus including a waste toner conveying path through which the waste toner is conveyed and an exhaust path through which the floating toner in the developing device is passed, such as a monochromatic printer, a monochromatic copying machine, a color copying machine, a multifunctional peripheral and a facsimile.

The invention claimed is:

1. A waste toner collecting device comprising:
an intermediate collection box in which a toner removed from an image carrier by a cleaning device is stored; a waste toner collection container in which the toner stored in the intermediate collection box is collected; a conveying path formed on a bottom face of the intermediate collection box; a conveying screw supported in the conveying path so as to be rotatable in a normal direction and in a reverse direction, the conveying screw conveying the stored toner toward the waste toner collection container by rotating in the normal direction; an exhaust path through which air containing a floating toner is sucked and passed; and a floating toner collection chamber provided on a part of the exhaust path and storing the floating toner separated from the air, wherein the floating toner collection chamber is provided in the intermediate collection box, and includes:
a discharge opening opened to an inside of the intermediate collection box; and
a discharge door which is interfered with the conveying screw as the conveying screw is rotated, and is turned between a storage position where the discharge opening is closed and a discharge position where the discharge opening is opened, wherein rotation of the conveying screw in the normal direction turns the discharge door into the storage position and rotation of the conveying screw in the reverse direction turns the discharge door into the discharge position so that the floating toner stored in the floating toner collection chamber is discharged in the conveying path through the discharge opening.

2. The waste toner collecting device according to claim 1, further comprising a biasing member which bias the discharge door into the storage position.

3. The waste toner collecting device according to claim 1, wherein the conveying screw has a rotating shaft and a spiral blade provided around the rotating shaft spirally in an axis direction of the rotating shaft at constant pitches, the discharge door has a protruding piece protruding in a space between the adjacent spiral blades in the axis direction, wherein when the conveying screw is rotated in the normal direction, an outer circumferential face of the

13

spiral blade presses the protruding piece in the normal direction to turn the discharge door toward the storage position,
when the conveying screw is rotated in the reverse direction, the outer circumferential face of the spiral blade presses the protruding piece in the reverse direction to turn the discharge door toward the discharge position.

4. The waste toner collecting device according to claim 3, wherein the protruding piece has a trapezoidal shape having a tip edge and side edges inclined in a direction where they are approaching each other toward the tip edge.

5. The waste toner collecting device according to claim 1, wherein the exhaust path has:
a floating toner duct, one end thereof connecting to an inside of a developing device, the other end thereof connecting to the intermediate collection box; and an exhaust duct, one end thereof connecting to the intermediate collection box, the other end thereof connecting to a suction fan,
the floating toner collection chamber forms the exhaust path between the floating toner duct and the exhaust duct.

6. The waste toner collecting device according to claim 5, wherein the intermediate collection box has:

14

a floating toner receiving opening connected to the other end of the floating toner duct; and an exhaust opening connected to the one end of the exhaust duct,

the floating toner collection chamber has:

a partition wall surrounding the floating toner receiving opening and the exhaust opening; and a lid part closing a space surrounded by the partition wall, wherein the discharge opening is provided on the partition wall and the discharge door is connected to the lid part.

7. The waste toner collecting device according to claim 1, wherein the floating toner collection chamber has a filter which blocks passing of the floating toner and allows passing of air,

the floating toner is separated from the air containing the floating toner by passing the air through the filter, collected by the filter and stored in the floating toner collection chamber.

8. The waste toner collecting device according to claim 7, wherein the discharge opening is disposed below the filter.

9. An image forming apparatus comprising:
a developing device which forms a toner image on an image carrier;
a cleaning device which removes the toner on the image carrier; and
a waste toner collecting device according to claim 1.
